UNITED STATES PATENT OFFICE.

GIUSEPPE BARTIROMO, OF LOS ANGELES, CALIFORNIA.

DESIGN FOR A FINGER RING.

Application filed March 6, 1928. Serial No. 25,715. Term of patent 7 years.

To all whom it may concern:

Be it known that I, GIUSEPPE BARTIROMO, a citizen of the United States of America, and a resident of Los Angeles, in the county of Los Angeles and State of California, have invented a new, original, and ornamental Design for Finger Rings, of which the following is a specification, reference being had to the accompanying drawing, forming a part thereof.

I claim:

The ornamental design for a finger ring as shown.

GIUSEPPE BARTIROMO.
